WRIST BAND ATTACHING MEANS FOR
WRIST WATCHES

Julius Dinhofer, New York, N. Y.

Application January 20, 1938, Serial No. 185,831

6 Claims. (Cl. 24—265)

This invention relates to band attachment means for wrist watches. The object of the invention is to provide a simplified means for attaching or connecting the ends of a wrist band or strap to a wrist watch. The construction of the improved device is such as to greatly facilitate the attachment or removal of the wrist band and provide a secure and positive means of attachment so that the possibility of the watch 5 becoming inadvertently disconnected from the wrist band and accordingly lost will be avoided.

According to present construction, the opposite ends of a wrist watch are each provided with a pair of lugs between which a rod or bar extends 15 and the same passes through a permanently-formed loop on the end of the wrist band. The rod or bar which connects the two lugs is usually provided with spring-pressed studs at its ends which snap into engagement with holes provided 20 in the lugs. An arrangement of this character is of relatively delicate construction, and to disconnect the ends of the wrist strap or band when it is desired to replace the band, often requires the use of tools. Also, it often occurs that when 25 replacing a wrist band the studs do not firmly engage the holes in the lugs and the band becomes later inadvertently disengaged from the watch and the watch lost.

With my improved wrist band connection 30 means, the cross bar or rod extending between the lugs may, if desired, be made integral with the lugs and may thus be of sturdy construction. Also, with my improved connection means, the ends of the wrist band may be very easily engaged 35 about the bar or rod without requiring removal of the bar or rod from its position between the lugs, so that the possibility of the watch becoming lost by faulty replacement of the bar is prevented.

In the accompanying drawing, wherein an embodiment of the invention is shown, Fig. 1 is a face view of a part of a wrist watch showing one of the ends of a wrist band attached thereto according to my invention, with parts of the band 40 broken away to disclose construction; Fig. 2 is a view of the rear face of the structure of Fig. 1; Fig. 3 is a perspective view of the stiffening member in its folded position, but removed from within the wrist band; Fig. 4 is a sectional view 45 on the line 4—4 of Fig. 1, looking in the direction of the arrows; Fig. 5 is a face view of one end of the wrist band before the same is bent into loop formation; and Fig. 6 is a sectional view on the line 6—6 of Fig. 2, looking in the direction of the 50 arrows.

In the drawing, 1 indicates the case of a wrist watch of conventional construction, such case being provided at each of its ends with the two spaced lugs indicated at 2, connected by the cross bar or rod 3 in the usual way. This cross-bar or rod 3 may be of the removable kind, or it may be a permanent member extending between the two lugs 2 and formed integral therewith. The wrist band or strap 4 may be formed of any suitable flexible material such as leather, fabric, 10 or the like, and it is preferably composed of several layers or plies, two of which are shown at 5 and 6 which are stitched together at their edges along longitudinal lines as at 7. Sandwiched between the two layers or piles 5 and 6, 15 near the end of the band, is a metal plate or stiffening member 8 held in position by means of the stitches 5 and 6 and also by means of transversely extending stitches 9 and 10, or other additional stitching if necessary.

The position of the strip 8 before being bent or doubled over to loop formation is shown in Fig. 5. Near one of its ends the strip 8 is provided with a pair of spaced, upwardly extending spring projections or tongues 11 and it is also 25 provided with additional projections 12 and 13 separated from the projections 11 by means of an intervening space 14. All of the projections 11, 12 and 13 are formed by distorting the metal of the body of the strip 8.

The band 4 is provided near its end with a cut-out opening 15 extending through the ply 5 and through which that portion of the strip provided with the various projections 11, 12 and 13 is exposed, as clearly shown in Figs. 2 and 5. 35 In placing the band on the watch, the end of the same is inserted between the watch and the bar 3 and the band and enclosed stiffening member 8 is bent to loop formation on the transverse line 16 in Fig. 5. The stiffening member or strip 8 in 40 the bent or doubled-over formation is shown in Fig. 3.

A sliding metal loop member 17 extends around the band and it is arranged to be forcibly moved into the space 14 between the projections 11, 12 45 and 13. The loop member 17 is formed on its under side with a depressed portion 18 which moves between the spring projections 11 and comes into contact or abutment with the stop 13. The additional stops 12 impinge against the ends 50 of the band so that when the band is moved toward the watch, its movement in that direction is limited by the stops 12 and 13. The spring projections or tongues 11, co-operating with fixed stops 12 and 13 confine it within the space 14 55

and hold it against inadvertent displacement. It will remain in the space 14 until it is manually drawn over the spring tongues 11 and moved in a direction away from the watch when it is desired to remove the band from its attachment to the watch. The metal comprising the strip 8 is of sufficient stiffness to cause the band to maintain its looped portion, and the loop 17, locked in position in the space 14 as heretofore described, provides a closed loop affording a secure means for holding the ends of the wrist band attached to the watch.

What I claim is:

1. A device of the character described comprising, a wrist watch band composed of several plies secured together, a flat metal strip disposed between the plies adjacent one end of the band, the band and the strip being both doubled over to form a bar-embracing loop, said strip having spaced stops, the band having an opening in one of its plies through which said stops are exposed, and a loop member extending around the band and adapted to be moved to embrace the doubled-over portions thereof and when so moved to be disposed between and restrained by the stops.

2. A device of the character described comprising a wrist band composed of two plies stitched together, a strip of flat metal located between the plies of the band near one end thereof, said strip being adapted to normally retain said end of the band in looped position, one of the plies of the band being formed with an aperture through which a portion of the strip is exposed, a loop surrounding the band and adapted to be moved to surround the doubled-over portions thereof to hold the end of the band in looped formation, and means on the exposed portion of the strip for engaging said loop and holding it in position around the doubled-over portions of the band.

3. A device of the character described comprising a wrist band having a flat metal strip inserted within it at one of its ends, said strip and band having portions in doubled-over forma-

tion, a loop on the band movable to extend around and embrace the doubled-over portions of the band and strip, and projections on the strip extending through the band and engaging said loop and holding it in position to embrace the doubled-over portions of the band and strip. 5

4. A device of the character described comprising a wrist band composed of two plies stitched together, a flat strip of metal disposed between the plies, one of the plies having an opening through which a portion of said strip is exposed, a loop member extending around the band, and spaced projections on the exposed portion of the strip between which the loop is engaged when said loop overlies the exposed portion of the strip. 10 15

5. A device of the character described, a wrist band having a stiffening member disposed within it and adapted to hold said band in doubled-over position at one of its ends when the band and contained stiffening member are transversely 20 folded together, a loop adapted to embrace the doubled-over parts of the band and stiffening member and hold the same in looped formation around a wrist watch bar, and means carried by the stiffening member for holding the loop 25 in position around said doubled-over parts.

6. A device of the character described comprising a wrist band composed of two plies stitched together, a strip of flat metal located between the plies of the band near one end thereof, said strip and band being doubled-over to normally retain said band in doubled-over or looped formation around a wrist-watch bar, one of the plies of the band being formed with an opening through which a portion of the strip is exposed, a loop extending around the band and adapted to be moved to overlie the exposed portion of the strip and surround the doubled-over portions of the band to hold the band in 30 35 40 loop formation, said exposed portion of the strip being formed with projections between which the loop is engaged when the loop overlies the exposed portion of the strip. 45
